DESIGN FOR A RABBIT BATTERY

Willard H. Jones, George T. Markey, and John B. Olson, Fort Atkinson, Wis., assignors to James Manufacturing Company, Fort Atkinson, Wis., a corporation of Wisconsin

Application April 4, 1938, Serial No. 76,260

Term of patent 14 years

To all whom it may concern:

Be it known that we, Willard H. Jones, George T. Markey, and John B. Olson, citizens of the United States and residents of Fort Atkinson, in the county of Jefferson and State of Wisconsin, have invented a new, original, and ornamental Design for a Rabbit Battery, of which the following is a specification, reference being had to the accompanying drawing, forming a part thereof.

The figure is a perspective view of a rabbit battery showing our new design. The side not shown in the figure is similar to the side shown.

We claim:

The ornamental design for a rabbit battery, as shown and described.

WILLARD H. JONES.
GEORGE T. MARKEY.
JOHN B. OLSON.
